ATTORNEY

UNITED STATES PATENT OFFICE.

TANNIE LEWIN, OF ST. LOUIS, MISSOURI, ASSIGNOR OF ONE-HALF TO WILLIAM LEWIN, OF ST. LOUIS, MISSOURI.

MOLD.

Application filed August 27, 1925. Serial No. 52,798.

- This invention relates generally to molds. More particularly, my present invention relates to a certain new and useful improvement in molds employed in the casting or 5 production of brass or bronze billets and has for its primary object the provision of a mold for enabling the economical, convenient, and facile production of especially billets of the kind mentioned.
- 10 And with the above and other objects in view, my invention resides in the novel features of form, construction, arrangement, and combination of parts hereinafter described and pointed out in the claim.
- 15 In the accompanying drawings, Figure 1 is a vertical sectional view and Figure 2 is a plan view of a mold embodying my invention.
- Referring now more in detail and by 20 reference characters to the drawing, which illustrates a preferred embodiment of my invention, A designates the body or matrix of the mold, which is of suitable dimensions and material and which includes a base 1, integral with or otherwise conjoined to 25 which is an upstanding preferably cylindrical portion 2 having a suitably elongated cylindrical cavity or casting-chamber 3 open at its one or upper end for billet-production. Projecting outwardly from the mold body-portion or matrix 2, are oppositely disposed lugs, trunnions, or the like 4 for facilitating the transport and manipulation of the mold proper A.
- 30 Adapted for removable disposition, as well as for axial turning or rotatory movement, upon the upper end of matrix 2 at the mouth of its chamber 3, is a member or so-called cap B, which is likewise of suitable material and of suitable dimensions 35 relatively to the mold proper A. Formed in the cap B and opening to its opposite ends, is a pouring or gate channel 5, which, as shown, tapers in diametrical dimensions from the 40 one or upper end of cap B to the other or under end thereof, where, as at 6, it discharges into the matrix-chamber 3. Also formed in the cap B and similarly opening to its opposite ends, is a riser-channel 7, 45 which is somewhat reduced in diametrical dimensions relatively to the gate-channel 5, but which likewise, as shown, tapers in diametrical dimensions from the upper end 50 of cap B to the under end thereof, where,
- as at 8, it is adapted for communication with the matrix-chamber 3. Projecting outwardly from cap B, is a pair of oppositely disposed lugs or the like 9 for both facilitating transport of the cap B and effecting rotatory or twisting movement of 55 the cap B upon the mold-body or matrix A.
- In use and operation, cap B is mounted or arranged upon the mold-body A at the open end of the casting-chamber 3, as best seen in Figure 1. The molten metal is then poured 60 into the chamber 3 through the gate-channel 5, the riser-channel 7 permitting the escape from the mold of air, gases, and other vapors, and the molten metal being so poured into the matrix A until the metal 65 substantially fills not only chamber 3, but also the channels 5 and 7. Upon then hardening or solidification of the metal, twisting movement is suitably imparted to the cap B, with the effect that the gate and riser are 70 sheared at the reduced ends 6 and 8 of the respective channels 5 and 7 from the billet so cast in the chamber 3. The cap B is thereupon bodily lifted and removed from the matrix A, when the billet proper, with 75 both its upper and lower ends substantially smooth and uniform, may be conveniently removed upon suitable manipulation of mold A from the chamber 3, and when also, upon suitable manipulation of cap B, the 80 gate and riser drop from the tapered channels 5 and 7 and are again usable on re-smelting.
- 85 By my new mold, I am thus enabled economically and conveniently, without waste 90 and obviating the present-day time-consuming and laborious billet-end finishing operations, to produce a billet finished and relatively smooth at its ends.
- I am aware that minor changes in the 95 form, construction, arrangement, and combination of the several parts of my new mold may be made and substituted for those herein shown and described without departing from the nature and principle of my 100 invention.
- Having thus described my invention, what I claim and desire to secure by Letters Patent is:
- In a billet-mold, an upstanding matrix 105 having a longitudinally disposed casting-chamber, said chamber being open at the upper end of the matrix, in combination

with a cap-casting rested upon the matrix and over the open end of said chamber, the cap being formed longitudinally with separate tapering pouring and riser channels 5 opening to the upper and lower faces of the cap and each adapted for communication at their reduced lower end with said chamber, the cap being smooth upon its under face and adapted for twisting movement upon the matrix for shearing the gate and riser 10 from the billet cast in said chamber.

In testimony whereof, I have signed my name to this specification.

TANNIE LEWIN.
